ATTORNEY

UNITED STATES PATENT OFFICE

EDWIN E. KRATZ, OF KANSAS CITY, MISSOURI

FOUNTAIN PEN

Application filed February 11, 1929. Serial No. 338,943.

My invention relates to fountain pens and more particularly to improvements in fountain pen caps.

In fountain pens, especially those not frequently used, the ink in the feed channel dries, necessitating priming or shaking of the pen before using, to start flow of ink to the pen point. It is therefore the principal object of my invention to so construct a fountain pen barrel and cap that withdrawal of the cap from the pen will automatically create a vacuum within the cap inducing flow of ink in the pen barrel toward the point of the pen.

In accomplishing this object of my invention I have provided improved details of structure, the preferred forms of which are illustrated in the accompanying drawings, wherein:

Fig. 1 is a view in elevation of a fountain pen equipped with a cap embodying my invention, the cap being in central longitudinal section.

Fig. 2 is a similar view illustrating the feeder and ink-duct of the pen in section.

Fig. 3 illustrates the pen and cap in separated relation with the ink-duct filled or primed for writing.

Fig. 4 is a transverse section of the cap on the line 4—4, Fig. 3.

Referring more in detail to the drawings:

1 designates a common type of fountain pen comprising a cylindrical barrel 2 having an externally threaded open end 3 for receiving a nipple 4 therein. Attached to a reduced neck 5 on the inner end of the nipple 4 is an ink sack 6 secured to the neck by a band 7. The nipple 4 is further provided with a restricted bore 8 in the neck portion terminating in an enlarged bore 9 in the outer end of the nipple for receiving a feeder 10 and a pen point 11. Extending longitudinally in the feeder adjacent the pen point is a ink-duct or fissure 12 for delivering ink from the reservoir or bore 9 to the nibs of the pen. The portion of the nipple projecting exteriorly from the barrel converges towards its outer end, terminating in an enlarged cylindrical end portion 13, which in accordance with my invention serves as a piston.

The parts heretofore described are of ordinary construction and do not constitute a part of my invention, except when employed in combination with the further elements presently described and that the end portion 13 of the nipple 4 is preferably of slightly greater diameter than is ordinarily employed. 55

14 designates a cap formed of hard rubber or other suitable material having a closed end 15 and a cylindrical bore 16 internally threaded near its outer end as at 17 for engagement with the externally threaded end of the barrel 2. 60

Seating with the bore 16 of the cap 14 is a sleeve or liner 18 also composed of hard rubber or other suitable material, the inner end of which abuts against the closed end of the cap and the outer end of which terminates adjacent the threads 17 in the bore 16 and has a counterbored portion 19 terminating in an outwardly tapered rim 20. The rim forms a mouth and is located to receive the piston 13 before the threaded end of the barrel engages the threads 17. 65

The counterbored portion 19 constitutes a cylinder of a diameter to snugly receive the piston 13 on the nipple 10 of the pen body, the increased diameter of the cylinder relative to the bore of the sleeve forming a stop-flange 21, for abutting the piston 13 when the cap is in position on the pen. The portion 19 is longer than the threaded portion 17 to permit the piston to move a substantial distance longitudinally in frictional engagement therewith. 70 80 85

Assuming the cap to be threaded on the barrel of the pen, the piston end 13 in sealing engagement with the cylinder or counterbored portion 19, and the ink as having receded from the ink-duct 12, when the pen is to be used, the cap is unthreaded from the pen barrel and removed from the barrel. 90

When the cap is moved over the piston portion 13 to remove the piston from the cylinder 19, a vacuum is created in the cap due to longitudinal movement of the portion 13 in sealing relation with the cylindrical wall of the cylinder 19, inducing a flow of ink into the ink-duct or fissure and to the pen point, 100

which renders the pen immediately ready for use.

Replacing the cap on the barrel in turn compresses the air in the cap, forcing the ink back into the reservoir. Alternate removal and replacement of the cap on the barrel creates a breathing action between the interior of the cap and the fountain pen, thereby maintaining a clean ink-duct and insuring free flow of ink to the pen point.

What I claim and desire to secure by Letters Patent is:

1. A fountain pen including a cylindrical cap, a liner in the cap including a counterbored portion having a cylindrical inner wall of substantial length and a tapered outer rim, and a pen barrel having a cylindrical nipple freely receivable in the cap and tapered rim of the liner and of sufficiently great external diameter to frictionally engage the cylindrical inner wall of the counterbored portion of the liner.

2. In a fountain pen, a barrel having a threaded open end portion, a nipple in the open end of the barrel having a cylindrical outer end forming a piston spaced from the open end of the barrel, a cylindrical cap having an internally threaded portion adjacent the open end of said cap to engage said threaded portion of the barrel, and a cylindrical portion of reduced diameter to slidably frictionally receive said piston, said last named cap portion having approximately the same length as said threaded portion to permit the piston to move a substantial distance longitudinally therewith, and a stop shoulder in the cap spaced from said threaded portion a distance equal to the spacing of the outer end of said piston from the threaded end of the barrel.

3. In a fountain pen including a barrel having an externally threaded open end portion and a nipple in the barrel having a cylindrical end forming a piston and having an outer end spaced outwardly from the threaded end of the barrel, a tubular cap having an internally threaded portion of substantially the same extent as the threaded portion of the barrel to engage the same, and a tubular liner in the cap having a tapering outer end located adjacent said threaded portion of the cap to receive the piston and provided with a cylindrical inner surface having an outer end edge spaced from the threaded portion of the cap a distance less than the spacing of the end of the piston from the barrel, said cylindrical surface having sufficiently small diameter to engage the piston sealingly, and having sufficient length to enable the piston to slide thereover to permit threaded engagement between the threaded portions of the barrel and cap.

In testimony whereof I affix my signature.
EDWIN E. KRATZ.
